UNITED STATES PATENT OFFICE

MATT R. HEMPHILL, OF GRAHAM, TEXAS

BAILER

Application filed September 6, 1929. Serial No. 390,791.

This invention is directed to an improvement in bailers for use in connection with oil wells and the like wherein provision is made for cleaning the bailer of accumulated and packed sand and the like acquired during the cleaning function of the bailer.

As is well understood, the bailer in its normal and conventional use withdraws from the well a very considerable portion of sand and like material, which in its accumulation in the bailer becomes so tightly packed, particularly in the lower portion of the bailer, that it is very difficult to dislodge in the cleaning of the bailer after the latter has been removed from the well.

Various attempts have been made to provide for cleaning the bailer by dislodging this tightly packed material, but such attempts have been proven to be practically insufficient as they were largely directed to a mere agitation of the material at local points, which while loosening the material at such points did not in any way tend to force the material through the outlet at the lower end of the bailer and were, therefore, ineffective.

The primary object of the present invention is the provision of an element within the bailer designed, during the cleaning operation, for relative rotation with respect to the bailer, the element being so formed that in this relative rotation the material, within the operative range of the element, is actually forced toward and through the outlet from the bailer in a positive and direct manner.

A further object of the invention is the specific formation of a combined valve, dart, and dislodging element to thereby insure accuracy of relative positions of these parts and guard against the possibility of separation except through breakage.

The invention is illustrative in the accompanying drawings, in which:

Figure 1 is a view in elevation of the improved bailer, the bailer casing being shown in section.

Figure 2 is a section on line 2-2 of Figure 1.

Figure 3 is a perspective view showing the valve, dart and dislodging element formed as a unit.

The bailer of the present improvement, aside from the details specifically hereinafter referred to, is of any conventional or preferred form, involving the elongated casing 1 of circular form and of appropriate diameter for introduction into the well. The casing is formed at its lower end with an opening 2 designed to be closed by a valve 3 against the interior of the bailer, this valve 3 having a depending stem 4, which as the bailer is lowered into the well, engages the bottom of the well to thereby open the valve and permit the sand and water, which it is desired to remove from the well by the bailer, to accumulate in the bailer.

The valve seat is preferably formed by a sleeve-like element 3' fitted within the lower end of the casing and riveted or otherwise secured thereto to insure substantial strength and rigidity at this point. The upper inner edge of the sleeve-like element 3' is appropriately formed to provide a seat for the valve 3, as indicated at 3".

As the bailer is withdrawn from the well, through the bailer handle 5 and connected chain or cable 6, the valve of course closes, permitting the material accumulated in the bailer to be withdrawn from the well, this being the conventional cleaning operation.

During the cleaning operation, the material accumulated in the bailer, largely sand and water, will arrange itself in the bailer with the sand at the lower portion and the water on top of the sand. The sand accumulating in the bailer is found to pack very tightly and solidly therein, and as the bailer, after it has been removed from the well, has of course to be cleaned from this accumulated material, the solid packed sand presents a

serious difficulty in any effective cleaning of the bailer.

Various attempts have been made to dislodge this comparatively hard accumulated body of sand in the lower portion of the bailer by agitating the sand at local points in an effort to loosen the same. This loosening of the sand at local points does not tend to a breaking up of the hardened mass in a manner to permit it to flow through the valve opening 2, and therefore all such attempts with which I am familiar have proven ineffective.

The present invention is designed to provide a means by which this accumulated hardened mass of sand is, at least throughout the hardened portion thereof immediately adjacent the valve opening 2, positively forced through such opening, and as the hardened mass is thus broken and dislodged by being forced through the opening, the remaining portions of the sand will by gravity be brought into contact with the dislodging means, and by it also forced through the opening, until the sand has reached such a stage of fluidity that it will freely gravitate through the opening.

The dislodging means forming the feature of the present invention is in the nature of a helical threaded member 7 connected to and rising from the valve 3, the helical convolutions of the member, indicated at 8, presenting comparatively broad operative faces. The usual stem 4 of the valve may, and preferably is for the purposes of the present invention, be provided with a conventional dart 9 having an opening 10, in order that during the cleaning operation the valve may be held open to discharge water, as is usual.

After the bailer with its accumulated body of sand is withdrawn from the well, it is held upright on the ground surface and the dart 9 engaged with the ground surface to open the valve 3 and at the same time hold the dislodging means 7 against rotation. The bailer proper, that is the casing 1, is then turned by hand relative to the dislodging member as an axis. The helical convolutions of the dislodging member 7 are thus forced to bite into the immediately surrounding mass of sand and not only break up this mass but positively and directly force the immediately surrounding material toward and through the casing valve opening 2. As the movement continues and the helical dislodging member removes the immediately surrounding portion of sand, other material will gravitate toward the dislodging member and be broken up and forced from the bailer by the relative movement between the dislodging member and bailer casing just described. This movement will be continued until the hardened mass is thoroughly broken up and discharged, or until the sand within the bailer has reached

a stage of fluidity which will cause it to freely gravitate through the valve opening 2.

The bailer with the improved dislodging means is thus effectively and readily cleaned of the accumulated hardened sand in a simple, expeditious manner without requiring any additional tools or the usual labor of inverting the bailer and dislodging the material by hand. A comparatively few turns of the bailer casing will serve to initiate the sand dislodging and discharging operations, and thereafter the cleaning function is quickly and easily carried out.

Experience has demonstrated that the hardened packed mass of sand is present only in the lower portion of the bailer, and therefore it is contemplated that the effective length of the dislodging element need only be that sufficient to reach through this hardened sand area. However, it is the intention to utilize the dislodging element for the effective operation and forceful displacing of the sand throughout this hardened area, and under these circumstances it is to be understood that there is to be no restriction as to the length of the dislodging element, and that any and all lengths of such element as may be necessary for the dislodging of this hardened material in the particular instance, are contemplated as within the spirit and scope of the present invention.

The preferred mode of operation is by fixing the dislodging element and rotating the bailer casing relative thereto. Obviously, the reverse operation is equally effective, namely holding the bailer casing against movement and rotating the dislodging element by a suitable tool. The effective function of this stage of the invention is the relative rotation between the dislodging element and bailer casing, without particular regard as to the manner in which this relative rotation is accomplished.

As an important but more specific feature of the invention, it is contemplated that the valve, dislodging member, valve stem and dart be constructed integrally from a single piece of metal in order to insure the advantages of rigidity in operation with little liability of separation of the parts in use. To this end, a cylindrical piece of appropriate metal of the desired diameter equalling the diameter of the valve 3 is flattened throughout an appropriate length above a portion which is left without change to form the valve. The material above this valve forming area is flattened, the upper surface of the valve gradually merging into the flattened portion. This flattened portion is then given the necessary twist to form the helical dislodging element. The material below the valve is also reduced in diameter and flattened out to form the stem 4 and dart 9. This specific arrangement is illustrated in Figure 3 and presents

the valve, dislodging member, stem and dart as an integral element.

What is claimed to be new is:

1. A bailer for oil and other wells, including a bailer casing, a valved opening at the lower end of the casing, a valve for said opening and means carried by the valve for breaking up and forcing the material within the bailer through the valved opening in the relative rotation of said means and bailer casing, said means being freely rotatable independently of the position of the valve.

2. A bailer for oil and other wells, including a bailer casing, a valved opening at the lower end of the casing, a valve for said opening and a helical dislodging element carried by the valve and extending within the casing, said dislodging element being freely rotatable independently of the position of the valve.

3. A bailer for oil and other wells, including a bailer casing, a valved opening at the lower end of the casing, a helical dislodging element carried by the valve and extending within the casing, and means beyond and wholly free of connection with the casing whereby the element may be fixed against rotative movement while permitting rotative movement of the casing.

4. A bailer for oil and other wells, including a bailer casing, having a discharge opening, a helical dislodging element extending within the casing, said element being designed for free rotative movement with respect to the casing, and serving during such movement for breaking up and by reason of its helical formation positively forcing the material within the casing through the discharge opening.

5. A bailer for oil and other wells, including a bailer casing, a valved opening at the lower end of the casing, a helical dislodging element carried by the valve and extending within the casing, and means having a transverse operating plane materially greater than the radius of the casing and means carried by the valve for fixing the element against rotation.

6. An accessory for oil and other well bailers, including an integral unit formed to provide a valve section for the bailer, a helical dislodging section above the valve section, said helical dislodging section having a diameter substantially equalling that of the valve, a stem below the valve section, and a dart at the terminal of the stem.

7. A bailer for oil and other wells including a bailer casing having a discharge opening, a valve for said opening, and a helical discharge member carried by the valve and extending into the casing, said discharge member being wholly free of any connection with the casing and being capable of operative rotation for discharge purposes in any position of the valve within the casing.

8. A bailer for oil and other wells including a casing having a discharge opening, a valve for the opening, and a helical discharge member carried by the valve and extending freely into the casing, said casing and helical discharge member being adapted for free uninterrupted relative rotation to cause the discharge member to dislodge the accumulated material throughout an area at least transversely coextensive with that of the valve opening.

In testimony whereof I affix my signature.

MATT R. HEMPHILL.
